STOPPING AND STARTING MECHANISM FOR LOOMS.

No. 848,815.

Specification of Letters Patent.

Patented April 2, 1907.

Application filed June 14, 1906. Serial No. 321,597.

To all whom it may concern:

Be it known that we, WILLIAM F. DRAPER and CHARLES F. ROPER, citizens of the United States, and residents of Hopedale, county of Worcester, State of Massachusetts, have invented an Improvement in Stopping and Starting Mechanism for Looms, of which the following description, in connection with the accompanying drawings, is a specification, like letters on the drawings representing like parts.

This invention relates more particularly to the mechanism which effects the starting and stopping of a loom; and it has for its object the production of means whereby the operation of such mechanism is greatly improved and its efficiency correspondingly increased.

As is well known to those skilled in the art and mechanism of weaving, the momentum of the moving parts of a loom is sufficient to keep up the motion or "turn the loom over," as it is technically termed, one or more times after the power is thrown off, and as it is desirable for many reasons to stop the loom promptly and with certainty when the power is thrown off it is customary to provide a brake for the purpose.

One very important reason for stopping the loom promptly, particularly when weaving lighter goods, is that by so doing thin places in the cloth are prevented, for the lay beats in the filling properly only when its momentum is brought into play, and when the power is thrown off the momentum decreases so rapidly that the complete beating in of the filling cannot be effected. The brake is accordingly set to stop the loom before the lay can beat up fully after the power is thrown off.

Heretofore the brake member or shoe has generally been given a very slight movement toward and from the coöperating annular member or pulley, on the crank-shaft usually, and in practice it is difficult to so adjust the mechanism that the brake will be sure to bear when it ought to, and yet be entirely clear of the coöperating pulley when it ought not to exert any braking action.

Owing to this difficulty of adjustment it is a matter of common observation that probably more than half of the loom-brakes nominally in use in mills are set back so far that they serve no purpose whatsoever.

In numbers of instances, by actual count, the brakes in operation and properly set have been less than one-fourth of the total number of looms running, the brakes on the other looms not only performing no function and exercising no control, but being so much dead-weight.

One of the objects of our present invention is to so-construct and arrange the mechanism that the brake can be set to operate properly without necessitating unusual care and skill, so that the benefits for which the brake mechanism is provided can be readily secured.

Another object of our invention is the production of means whereby the brake is not applied until the power is thrown off completely and the brake released, freeing the loom from its control before the power is thrown on.

At present looms are so constructed that when the shipper is released or thrown off the driving-belt is shifted from the fast to the loose pulley, and before such shifting is effective the brake is applied, so that the belt is straining against the brake, resulting in wear to both and waste of power.

The breakage of lay-swords and other parts of the loom, owing to the special strains set up, are frequently due to this pull of the belt against the action of the brake. The converse is equally true, for the belt is moved part way onto the fast pulley before the brake is released, when the shipper is moved to start the loom, and to the inertia of the parts at rest is added the resistance of the brake, which must be overcome by the belt as it is shifted onto the fast pulley.

By our present invention we obviate entirely such objectionable and unnecessary strains on the mechanism, wear and tear, and loss of power, and thereby increase the efficiency, life, and smoothness in operation of the loom.

The various novel features of our invention will be fully described in the subjoined specification and particularly pointed out in the following claims.

Figure 1 is a left-hand side elevation of a sufficient portion of a loom with one embodiment of our present invention applied thereto, the brake being off and the shipper in running position. Fig. 2 is a top plan view

thereor centrally broken out to show clearly the relative position of the various parts of the mechanism and their construction and mode of operation. Fig. 3 is a front elevation of the shipper in running position and the parts adjacent thereto. Fig. 4 is a similar view, but with the shipper in stopping position, and when in such position the brake is on and the power off the loom. Fig. 5 is a front elevation, centrally broken out, showing both sides of the loom and with the driving-belt fully on the loose pulley, the brake being just about to act.

Referring to Figs. 1 and 2, we have herein shown the loom sides 1, connecting breast-beam 2 and the driving or crank shaft 3, by or through which motion is transmitted to the lay and other moving parts of the loom, all of substantially well-known construction 20 in power-loom, and herein said shaft is provided with fast and loose pulleys 4 5, Figs. 2 and 5, adapted to be driven from a suitable source of power by a belt B. Herein the pulleys are shown at the right-hand side of the 25 loom, and at the opposite side the shaft 3 has fast upon it a fly-wheel 6, which also forms the annular rotatable member of a brake device for the loom, the coöperating member being shown as a shoe or segmental member 30 7, pivotally mounted at 8 on the loom side.

The belt-shifter or fork 9, secured to or forming part of a sleeve 10, slidably mounted on a supporting-stud 11, projecting laterally from the loom side, the arm 12 on the sleeve 35 coöperating with the guide-bracket 13, and the rod or link 14, attached at one end to the sleeve 10 and at its opposite end to one extremity of the rocking bent lever 15 16, may be and are of substantially usual construction, rocking of the lever on its fulcrum 17 40 moving the belt-shifter 9 in or out to shift the driving-belt from one to the other of the two pulleys on the driving-shaft 3 to thereby throw the power onto or off of the loom, as will be manifest. The rocking of said lever is effected by or through movement of the shipper 18 from running to stopping position, and vice versa, the shipper being fulcrumed at 19, Figs. 3, 4, and 5, and thrown into stopping position by the spring 20 when released from the notch 21, Fig. 2, in the slotted holding-plate 22.

In our present invention we have considerably increased the amplitude of movement of the shipper from one to the other of its extreme positions in order that the shifting of the power onto or off of the loom shall be effected after release of the brake or before the latter is applied, respectively, as will be explained. The shipper is provided with a socket 23 to receive the end of the lever-arm 16, a removable pin 24 retaining the parts in coöperative relation while permitting disconnection when desired.

When the shipper is in running position,

Figs. 1, 2, and 3, the connections between it and the belt-shifter 9 will position the latter, as shown in Fig. 2, with the belt B in full driving engagement with the fast pulley 4, and at such time the brake is off, the brake-actuating means being described hereinafter. Now when the shipper is released from its holding-notch and moved to stopping position the belt-shifter is moved to shift the belt from the fast to the loose pulley, and the mechanism herein is so arranged that the belt is entirely off the fast pulley when the shipper reaches a predetermined point in its movement toward stopping position; such point being some distance from final stopping 80 position.

Referring to Fig. 5, it will be seen that the belt B has been shifted completely from the fast pulley onto the loose pulley 5 when the shipper has reached an intermediate position 85 I on its way from running position, (indicated at R,) the position I being the predetermined point hereinbefore referred to. At this point the application of the brake is effected, but as the power has been completely 90 thrown off it will be manifest that there cannot be any strain or wear on any of the mechanism due to braking action while the power is on, even if only partly so.

Referring to Figs. 1 and 2, the brake member or shoe 7 is connected by a rod or link 25 with the usual loom-frog F, arranged to knock off or release the shipper when said frog is operated by or through the usual protector mechanism. (Not shown.) An adjustable stud 30 on a collar or head 26 on the link 25 is adapted to be engaged by the upturned short arm 27 of a lever fulcrumed on the loom side at 28, the long arm 29 of the lever being extended forward and supporting 100 a weight W, which when free to act swings lever 27 29 on its fulcrum and through the link 25 applies the brake, the lever and weight constituting a brake-actuator. Owing to the great difference in leverage of the 105 arms 27 29, the descent of the weight W acts to apply the member or shoe 7 with great force against the periphery of the annular member 6, effectually and quickly stopping the loom—so promptly, in fact, that the lay 110 cannot beat up after the brake is applied, thus preventing the formation of thin places in the cloth. This brake mechanism in its general construction is not of our invention, but we have so constructed the same that the movement of the brake member 7 toward 115 and from the member 6 is augmented materially—that is, such movement is large relatively to what would be an absolutely necessary movement to effect engagement or disengagement of the brake members. Easy adjustment or setting of the brake without the exercise of great care is thereby permitted, and the movement of the member 7 is relatively so great that it is absolutely and 120 125 130

entirely away from the coöperating member 6 when the brake mechanism should be inactive, yet will surely act at the proper time on the member 6 to stop the loom.

5 The lever-arm 29 extends forward across the plane in which the shipper moves, Fig. 1, and is provided with a lateral extension 31, adapted to be at times engaged by a rigid finger 32 on the shipper, projecting therefrom adjacent its fulcrum-point and rounded at its extremity, as at 33, to reduce friction when in engagement with the extension.

Taking, first, the case wherein the shipper is in running position, Figs. 1, 2, and 3, it will be observed that the finger-tip 33 is in its most elevated position, lifting the extension 31, and through the lever 15 16 lifting the weight and moving the brake member 7 to its extreme position away from the annular member 6.

When the shipper is released from its holding-notch 21 and is moved by its spring 20 toward stopping position, the finger 32 swings downward, the weight W causing the extension 31 to follow, and when the intermediate position I of the shipper, Fig. 5, is reached the power will have been entirely thrown off, but the brake has not yet been applied. It is just ready to act, however, the two brake-surfaces being almost in contact, and as the shipper moves past position I, dropping the finger 32, the weight W instantly applies the brake, and the loom is stopped.

35 The movement of the extension 31 from the position shown in Fig. 5 to that shown in Fig. 4 is very slight, but it will be understood that at such time the movement of the brake member 7 has only to be from non-contact to complete contact with the member 6, a very slight distance indeed in actual practice. The greater movement has been effected during the movement of the extension 31 from running position, Fig. 3, to intermediate position, Fig. 5.

When the shipper is in stopping position, Fig. 4, and as indicated at S, Fig. 5, the finger is entirely disengaged from the extension.

If it be desired to throw off the brake by hand without moving the shipper, the bell-crank 34 is turned in the direction of arrow 35, Fig. 4, to thereby lift the link 36, which passes through a hole in the lever-arm 16 and is enlarged or headed at its lower end at 37. Such device for throwing off the brake by hand when the loom is at rest is not a part of our present invention, however.

Supposing the loom to be at rest, the shipper being in the position shown in Fig. 4 and at S, Fig. 5, with the brake on and the power off. To start the loom, the shipper is moved to the right, Fig. 5, and the finger 32 as it rises will engage and lift the extension to the position shown in Fig. 5 when the intermediate shipper position I is reached. The

brake is now off, as the members 6 and 7 have been disengaged, and the loom is free to start, but no shifting of the belt B from loose to fast pulley has yet taken place. (See Fig. 5.) When, however, the shipper passes the intermediate point at I, the lever 15 16 acts at once through the rod or link 14 and throws the belt-shifter into the position shown in Fig. 2, moving the belt onto the fast pulley 4 completely as the shipper reaches the holding-notch 21 in running position, Fig. 5. As the movement of the shipper from I to R is effected the separation of the brake members is completed. Thus in starting the loom there is no chance for the brake to act against the power, and all strains due to such action are wholly obviated.

It has been found that the greater amplitude of movement of the shipper as herein provided permits of easier operation on the part of the weaver, requiring less expenditure of power, which is a very advantageous feature.

Automatic release of the shipper upon the occurrence of a filling fault is effected through the usual filling-fork mechanism (indicated at F^X, Figs. 1 and 2) and the knock-off lever 38, and in case the loom is provided with a warp stop-motion the loom can be stopped automatically.

A sufficient portion of a warp stop-motion is shown in Fig. 1, the same being substantially as shown in United States Patent to Sawyer, No. 763,119, a knock-off arm 47, fulcrumed on the loom-frame, having a cam-slot 48, through which the lower end of the shipper 18 extends, the knock-off arm being operated from the warp stop-motion by or through the link 45.

Further illustration or description of this mechanism is unnecessary herein.

When the loom is stopped by automatic release of the shipper, the construction herein is such that the lay A³ is stopped at a substantially fixed point, with the shuttle boxed in one or other of the usual shuttle-boxes in readiness to be picked when the loom is started without further attention by the weaver.

The brake mechanism is brought into condition for instant application by or through movement of the shipper from running position to a predetermined point, the power being wholly thrown off the loom when such point has been reached, and as the shipper passes beyond such point the operation of the brake mechanism is instantly and completely effected. Stoppage of the driving or crank shaft is thus effected at a substantially fixed point upon automatic shipper release, and manifestly the connected lay is stopped simultaneously.

Our invention is not restricted to the precise details of construction and arrangement herein shown and described, as the same may

be modified or varied by those skilled in the art without departing from the spirit and scope of our invention.

Having described our invention, what we claim as new, and desire to secure by Letters Patent, is—

1. In a loom, in combination, a shipper, a brake, fast and loose pulleys to coöperate with a driving-belt, and means controlled by movement of the shipper to stopping position to shift the belt wholly from the fast onto the loose pulley before the brake is applied, said means also acting to throw off the brake positively and entirely before the belt is shifted onto the fast pulley by movement of the shipper to running position.

2. In a loom, in combination, a driving-shaft provided with fast and loose pulleys to coöperate with a driving-belt, a brake for said shaft, a shipper, and means controlled by movement thereof to stopping position to shift the belt onto the loose pulley and thereafter effect the application of the brake, and to positively throw off the latter, before the belt is shifted onto the fast pulley, by movement of the shipper to running position.

3. In a loom, in combination, a driving-shaft provided with fast and loose pulleys to coöperate with a driving-belt, a brake for said shaft, an actuator for the brake, a shipper, and means controlled by movement thereof to stopping position to wholly shift the belt to the loose pulley and thereafter permit the actuator to apply the brake, and to positively render the actuator inoperative and release the brake before the belt is shifted from loose to fast pulley, by movement of the shipper to running position.

4. In a power-loom, in combination, a brake an actuator therefor, a shipper coöperating with said actuator, to automatically and positively release the latter upon stopping movement of the shipper, to apply the brake, and means governed by such shipper movement to throw off the power from the loom before the brake-actuator is released.

5. In a power-loom, in combination, a brake, an actuator therefor, a shipper, means governed by movement of the shipper from running position to a predetermined point to wholly throw off the power from the loom, and means operative on shipper movement beyond such point toward stopping position to cause application of the brake by its actuator independently of the shipper.

6. In a power-loom, in combination, a brake, an actuator to apply it, means to throw the power onto and off of the loom, and a shipper to govern said means and the brake-actuator, movement of the shipper from running position to a predetermined point throwing off the power and thereafter permitting the actuator to apply the brake, while reverse movement from stopping posi-

tion to such point causes the actuator to positively release the brake, continued movement to running position throwing the power onto the loom.

7. In a loom, in combination, an annular, rotatable brake member, a coöperating segmental member having a two-part movement toward and from the annular member, a shipper, a brake-actuator controlled thereby, and means movable with the shipper, whereby one part of the movement of the segmental brake member is simultaneous with, and the other part of such movement independent of the shipper movement, thereby providing for easy adjustment of the segmental member, and insuring absolute disengagement of both members when the shipper is moved to running position, and absolute engagement when the shipper is moved to stopping position.

8. In a loom, in combination, an annular, rotatable brake member, a coöperating segmental member having an extended or augmented movement toward and from the annular member whereby easy adjustment of the segmental member is provided and absolute engagement or disengagement of said members insured, a shipper, a brake-actuator controlled thereby and separate therefrom, and means to throw power onto and off the loom by movement of the shipper from stopping to running position, and vice versa, respectively, shipper movement from stopping position operating through the actuator to positively and completely disengage the brake members before the power is thrown on, reverse shipper movement permitting the actuator to positively effect engagement of said brake members after the power is thrown off.

9. In a power-loom, in combination, a driving-shaft adapted to effect reciprocation of the lay, brake mechanism, a shipper, and means governed by movement of the shipper from running position to a predetermined point to wholly throw off the power and bring the brake mechanism into condition for instant operation, movement of the shipper past such point causing immediate and full operation of the brake mechanism by said means, independently of the shipper, to stop rotation of the driving-shaft at a substantially fixed point.

10. In a power-loom, in combination, a driving-shaft adapted to effect reciprocation of the lay and having an attached annular brake member, a coöperating segmental member having an augmented movement toward and from the annular member, a shipper, and means separate from the shipper and governed by movement thereof from running position to a predetermined point to wholly throw off the power and positively move the segmental member into position for instant coöperation with the annular

brake member, movement of the shipper past such point causing immediate and complete coöperation of said rotatable and segmental brake members, by or through said means, to stop rotation of the driving-shaft at a substantially fixed point.

In testimony whereof we have signed our

names to this specification in the presence of two subscribing witnesses.
